UNITED STATES PATENT OFFICE.

OWEN R. DAILEY, OF DAVENPORT, IOWA, ASSIGNOR OF ONE-FOURTH TO CLARENCE C. HAZARD, OF SCOTT COUNTY, IOWA.

TOY TOP.

Application filed December 27, 1926. Serial No. 157,216.

My invention relates to an improvement in toy tops.

The objects of my invention are to provide a simple economically constructed top which, when rapidly spun, will automatically be inverted so as to spin upon the end of its handle instead of upon the point, but which can be spun slowly enough to allow the handle to remain upward.

I attain these objects by the devices illustrated in the accompanying drawings in which,—

Figure 1 is a side elevation of one form of my top showing the pivot stick extending through the body of the top, in dotted lines; Fig. 2 is a top or plan view; Fig. 3 is a side elevation showing the top with the pivot in horizontal position and Figure 4 is a side elevation of the top in inverted position; Fig 5 is a vertical cross-section view of an alternative form of my top in which weights of heavier material are inset into the body of the top to take the place of the bulges shown in Figures 1 to 4; Fig. 6 is a vertical cross-section on the center line of another form of the top in which the body is formed of a hollow casing such as sheet metal, with weights secured to the inside thereof; Fig. 7 is a plan view of an alternative form of my top showing a plurality of upper and lower weighted portions.

My top preferably comprises a spherical body, 2, formed of solid material and with a pivot stick or handle preferably extending through the center of the body and projecting at the upper end to form a handle, 1, and projecting at the lower end slightly to form a point, 5, upon which the top can be spun.

The body is formed with a slight protuberance, 4, upon one side between the middle line of the body and the handle and a corresponding protuberance, 3, diametrically opposite thereto, which would bring it between the middle line of the body and the point, 5.

The object of these protuberances is to give added weight at the points at which they are located and when the top is spun rapidly while resting upon the point, 5, the centrifugal motion of these protuberances will tend to tip the upper portion of the body to the left and to propel the lower portion of the top upwardly and to the right. As this action continues, the top will successively get into the horizontal position shown

in Figure 3 and then into the inverted position shown in Figure 4. It is necessary to spin the top quite rapidly in order to accomplish this change of position. When the top is spun slowly upon the tip, 5, the handle 60 will remain in the vertical position.

It is, of course, immaterial whether the increased weight is added to the globular body at the points shown by forming enlargements or protuberances such as 3 and 4, thereon, or whether it is done by inserting weights such as 3^a and 4^a into suitable insets or pockets cut out of the globular body. When desired to form the top from a hollow sphere, the sphere may be formed of light 70 sheetmetal and the weights, 3^b and 4^b, united thereto by soldering small lumps of solder or other suitable metal thereto, or the halves of the globe may be die-cast and the weighted portions die-cast integral with the shells 75 thereof.

Obviously, the same result may be produced by using a plurality of weighted portions, 6 and 7, as shown in Figure 7, the portions, 7, being shown in dotted lines and 80 being diametrically opposite from the weighted portions, 6.

Obviously various other forms of attaching the weights to the top may be utilized without departing from the principle of my invention, the top may be formed with a smooth surface or the surface may be figured and painted or decorated in various ways, and the pivot stick or handle and point may be formed integral with the body.

In the operation of my top, when it is desired to spin it in the upright position shown in Figure 1, the handle, 1, is grasped between the thumb and second finger and subjected to a whirling motion sufficient to produce the revolution of a top at a moderate speed. When it is desired to cause the top to automatically invert itself and assume the position shown in Figure 4, the handle of the top is grasped in the same manner and it is spun rapidly. This will cause the top to tilt over until the handle, 1, strikes the table or other support upon which it is spinning and it will then leap into the inverted position shown in Figure 4 and spin 90 in that position until slowed down by friction.

When the top is spun rapidly on the point, 5, the centrifugal and gyroscopic forces will cause it to be inverted into the position 100 110

shown in Figure 4 and to so remain. When it is spinning in the position shown in Figure 4, the length of the handle raises the body above the floor and causes the weighted portion, 4, 4^a, 4^b, to revolve in a position approximately midway between the outer end of the handle, 1, and the point or tip, 5, of the top and the revolution in this position seems to stabilize the top and cause it to continue to spin upon the handle, 1.

I claim:

1. A top comprising a substantially globular body having diametrically opposite projecting portions formed integral therewith upon an axial line at an angle of approximately 45° to the vertical axis of the top, a pivot point united to the top at the lower end of the vertical axis thereof, and a handle united to the upper side of the top in line with the vertical axis thereof.
2. A top comprising a substantially globular body having diametrically opposite weighted portions of said globe secured at an angle of approximately 45° to the vertical axis of the top, a pivot point united to the top at the lower end of the vertical axis thereof, and a handle united to the upper side of the top in line with the vertical axis thereof.
3. A top comprising a substantially globular body having a handle and pivot point secured thereto upon its vertical axis and having diametrically opposite weights secured to said body intermediate its vertical and horizontal axes.
4. In a top, the combination with a globular body, of a handle and pivot point suitably united thereto and means secured between the handle and the horizontal median line and between said median line and the pivot point respectively, adapted to exert centrifugal force in opposite directions upon the upper and lower portions of the top when spun rapidly.
5. In a top, the combination with a globular body, of a handle and pivot point suitably united thereto and means secured between the handle and the horizontal median line and between said median line and the pivot point respectively, adapted to exert centrifugal force in different directions upon the upper and lower portions of the top when spun rapidly.
6. A top comprising a substantially globular body having diametrically opposite projecting portions formed integral therewith upon an axial line at an angle of ap-

proximately 45° to the vertical axis of the top, and a handle united to the upper side of the top in line with the vertical axis thereof.

7. A top comprising a substantially globular body having a handle secured thereto upon its vertical axis and having diametrically opposite weights secured to said body intermediate its vertical and horizontal axes.

8. A top comprising a substantially globular body having weighted portions formed integral therewith at diametrically opposite points between the middle and top and the middle and bottom of the top respectively, and means for spinning same.

9. A top comprising a substantially globular body having protuberances formed integral therewith at diametrically opposite points between the middle and top and the middle and bottom of the top respectively which protuberances weight the top unevenly, and means for spinning same.

10. An automatically reversing top comprising a globular body having the weight of its upper and lower halves respectively unevenly distributed with reference to its vertical axis.

11. An automatically reversing top comprising a globular body having the weight of its upper and lower halves respectively unevenly distributed with reference to its vertical axis and a handle for spinning same secured to the top in line with its vertical axis.

12. An automatically reversing top comprising a hollow substantially globular body having the weight of its upper and lower halves respectively unevenly distributed with reference to its vertical axis.

13. An automatically reversing top comprising a hollow substantially globular body having the weight of its upper and lower halves respectively unevenly distributed with reference to its vertical axis and a handle for spinning same secured thereto in line with its vertical axis.

14. An automatically reversing top comprising a hollow substantially globular body having the weight of its upper and lower halves respectively unevenly distributed with reference to its vertical axis and a handle and pivot point for spinning same secured thereto in line with its vertical axis.

In testimony whereof he affixes his signature.

OWEN R. DAILEY.
